[57] **CLAIM**

The ornamental design for a combined storage chest and table, substantially as shown and described.

DESCRIPTION

FIG. 1 is a right perspective view of a combined storage and chest and table showing my new design, the broken line showing of a shed being for convenience of illustration;

FIG. 2 is an enlarged left perspective view thereof;
FIG. 3 is a right side elevational view thereof, the left side elevational view being substantially a mirror image thereof;

FIG. 4 is a bottom plan view thereof;

FIG. 5 is a rear elevational view thereof.

FIG. 1

FIG. 2
